MINER'S SHIRT AND GARMENT PROTECTOR

Filed Feb. 15, 1928

Annie E. Miller

P. L. Thomas

INVENTOR

BY *Victor J. Evans*

WITNESS:

ATTORNEY

UNITED STATES PATENT OFFICE.

ANNIE E. MILLER, OF NEWTON HAMILTON, PENNSYLVANIA.

MINER'S SHIRT AND GARMENT PROTECTOR.

Application filed February 15, 1928. Serial No. 254,485.

This invention relates to apparel and its general object is to provide a garment primarily designed to protect the shirt or other garment of a person working in mines and the like where it becomes necessary at times to crawl from place to place in narrow passages and the like, where the back comes in contact with the upper wall of the passages.

A further object of the invention is to provide a miner's shirt and garment protector, that is simple in construction, inexpensive to manufacture and efficient in service.

This invention also consists in certain other features of construction and in the combination and arrangement of the several parts, to be hereinafter fully described, illustrated in the accompanying drawings and specifically pointed out in the appended claim.

20 In describing my invention in detail, reference will be had to the accompanying drawings wherein like characters denote like or corresponding parts throughout the several views, and in which:

25 Figure 1 is a front elevation of the garment which forms the subject matter of the present invention.

Figure 2 is a sectional view taken approximately on line 2--2 of Figure 1, looking in 30 the direction of the arrows.

Referring to the drawings in detail, the reference numeral 1 broadly indicates the body of the garment which may be formed from a number of pieces of material or from 35 a single piece as shown. The body includes a back 2 having formed therewith side portions 3 and front portions 4.

The front portions are arranged in spaced relation with respect to each other and are 40 cut away in circular formation to cooperate with cut away portions formed in the sides of the back and side portions to provide arm receiving holes 5. While I have shown the arm receiving holes as being finished and 45 reinforced by strips of material 6 stitched about the edge thereof in the usual manner, I want it understood that I may provide the garment with sleeves as shown in dotted lines in Figure 1.

50 The body is provided with a reinforcing band 7 extending about the top thereof, as shown, and this band as well as the opening which it surrounds is of sufficient size to snugly engage the shoulders of a person ad-

jacent the juncture of the neck therewith. 55 The band is of course sewed about the top and a similar band 8 extends about and is sewed to the bottom of the garment, while strips 9 are sewed about the lower edge of the front portions. 60

The garment may be formed from canvas or like wear resisting material and is secured about a person through the instrumentality of straps 10 having one of their ends secured in any appropriate manner to one side edge 65 of one front portion and the edge of one side portion, and preferably to the bands 7 and 8 and the strip 9 of the one front portion, as shown in Figure 1 of the drawings. The straps are provided with openings so 70 as to be adjustably received by buckles 11 which are likewise secured to the bands 7 and 8 and other strip 9.

The front portions 4 are provided with pockets 12 which may be formed with flaps 75 13 adapted to be secured in closed position through the medium of a button and button hole connection as shown.

While I have shown buckles for securing the garment on a person, I want it understood that I may employ hooks, snap fasteners or any other desired fastening means without departing from the spirit of the invention and the fastening means is arranged on the side of the protector so as to not interfere with the wearer. 80 85

From the above description and disclosure of the drawings it will be obvious that I have provided a miner's shirt and garment protector, which may be easily and expeditiously secured about a person, and will completely cover the back and sides of a shirt or other garment worn by the person so as to amply protect the same from wear, tear and dirt when crawling and passing through 90 95 narrow passages of a mine or the like.

It is thought from the foregoing description that the advantages and novel features of my invention will be readily apparent.

I desire it to be understood that I may 100 make changes in the construction and in the combination and arrangement of the several parts, provided that such changes fall within the scope of the appended claim.

What I claim is:

105 A garment of the character described comprising a body including a back portion, front portions formed with said back por-

tion, pockets secured to said front portions, the bands and one of the strips, buckles secured to the opposite ends of said bands and other strip respectively, and being 10
5 side portions formed with said back portion, a band sewed to the lower edge of the back and side portions, a band sewed to the upper edge of the back and front portions, strips adapted to receive the straps for adjustably sewed to the bottom of the front portions, straps having one of their ends secured to securing the garment about a person.

In testimony whereof I affix my signature.

ANNIE E. MILLER.
